UNITED STATES PATENT OFFICE.

RAYMOND C. FISHER, OF ROCHESTER, NEW YORK, ASSIGNOR TO NORTH EAST ELECTRIC COMPANY, OF ROCHESTER, NEW YORK, A CORPORATION OF NEW YORK.

GROUND CONNECTION.

Application filed January 25, 1923, Serial No. 614,884. Renewed October 16, 1925.

In an electrical apparatus provided with a metallic frame or casing and with an insulated binding-post, it is often desirable to provide a connection or "ground" between the binding-post and the casing; and this is commonly done by means of a conductive bond or strap secured, at one end, to the binding-post, the other end of the strap being secured to the casing.

10 The object of the present invention is to provide a ground-connection, for the purpose just set forth, which shall be simple, effective, and neat in appearance. To this end I use a cup-shaped conductor which is mounted upon and concentric with the binding-post and which spans the insulation of the post, and makes conductive contact with the casing at its annular margin.

15 A preferred embodiment of the invention is illustrated in the accompanying drawings, in which Fig. 1 is a sectional elevation of a ground connection, and Fig. 2 is a bottom view of the same.

20 The invention is illustrated as used in connection with a binding-post 3 which is embedded in and supported by a body 4 of insulating material. The body 4 is supported on a metal plate 5 which may constitute a part of the casing of an electrical apparatus.

25 The binding-post has the usual threaded ex-

tremity, to which wires or terminals may be secured by nuts.

The novel grounding-device is in the form of a cup 6 drawn from sheet-metal and perforated centrally to receive the threaded portion of the binding-post. This cup is 35 preferably bent outwardly at its free margin 7 and at this point it engages the surface of the plate 5. When a nut 8 is screwed home on the binding-post it presses the cup 40 firmly against the plate, and a spring lock-washer 9 may be used to prevent accidental loosening of the parts.

45 It will be apparent that this grounding-device may be very easily applied and that it requires no parts for securing it in operative position, other than those provided for the ordinary use of the binding-post.

The invention claimed is:

50 The combination, with a binding-post projecting through, but insulated from, a conductive body and provided with screw-threaded fastening means, of a grounding-device in the form of a metal cup, centrally perforated to receive said fastening-means, 55 the free edge of the cup being pressed into engagement with the surface of said conductive body around the binding-post.

RAYMOND C. FISHER.
